PRESSURE CONTAINER

Arnold H. Heineman, Birmingham, Ala., assignor
to Chicago Bridge & Iron Company, a corpora-
tion of Illinois

Application January 22, 1941, Serial No. 375,491

1 Claim. (Cl. 220—1)

This invention relates to improvements in pressure containers or tanks and more especially to such a container built of sheet metal.

My invention is especially adapted for use in connection with underground tanks and is so illustrated in this specification.

Among the features of my invention is the making of such a tank capable of withstanding considerable internal pressure both positive and minus. The tank is also so constructed that considerable earth loads may be borne. Another feature of my invention is the provision of such a tank made out of plates that are either flat or bent in one plane only. The expense of shaping plates to double curvature is therefore avoided.

Other features and advantages of my invention will appear more fully as I proceed with my specification.

In that form of device embodying the features of my invention illustrated in the accompanying drawings, Fig. 1 is a top plan view with a portion of the top cut away; Fig. 2 is a view in side elevation with a portion of the wall cut away; Fig. 3 is an enlarged fragmentary vertical sectional view; Fig. 4 is a top plan view of one of the posts; Fig. 5 is a view in side elevation similar to Fig. 2 showing a modified form; Fig. 6 is a view similar to Fig. 3 showing another modification; Fig. 7 is a view similar to Fig. 5 showing another modification; and Figs. 8-13 are diagrammatic vertical sectional views showing additional modifications.

As shown in the drawings, the tank includes a circular substantially flat top 10 and a circular substantially flat bottom 11 of considerable area connected at points spaced throughout the areas by structural posts 12 to secure the same against displacement. Such a tank, for example, may be 10 feet or more high and have a diameter from 50 to 100 feet to give the same a capacity of from approximately 2,500 barrels to approximately 13,000 barrels or more. The spacing of the posts 12 will depend upon the pressure to be carried. For example, they may be spaced from each other 2 feet, more or less.

The side wall of the tank is circular in horizontal cross-section and is formed of two or more frusta of cones. In the construction of Figs. 1-4 there are four such frusta, namely 13, 14, 15 and 16, counting from the top downwardly. The upper two taper downwardly and inwardly whereas the lower two taper downwardly and outwardly. In the modified form shown in Fig. 5 the side wall comprises only two such frusta,

namely an upper 113 tapering downwardly and inwardly and a lower 116 tapering downwardly and outwardly.

If desired, there may be provided at intervals outside of the tank, bracing plates 17 with their inner edges connected to the side wall and provided with an outer straight edge extending from the periphery of the top to the periphery of the bottom. This straight edge is preferably braced with an angle-iron 17a. A similar bracing plate is indicated in the modified form of Fig. 5 by 117.

The construction of the posts 12 forms no part of the present invention but I have here shown them as made of angle-irons so that the complete post is narrowed somewhat at the center to resemble the shape of an hour glass. The posts are welded at their upper and lower ends to the top and bottom, respectively, so that they will withstand both compression and tension.

20 The plates 17 and 117 are also welded at their inner edges to the side wall. In fact, it is to be understood that all adjacent parts are suitably attached as by welding or in any other suitable manner in order to make a rigid construction.

25 It is also to be understood that the frusta of cones forming the side wall may convex outwardly instead of concaving inwardly as shown. Such construction is indicated diagrammatically in Fig. 6. In such case a bracing plate may be placed inside. For example, as shown in Fig. 6 the top is indicated by 210, the bottom by 211 and the frusta of cones forming the side wall by 213, 214, 215 and 216, respectively. Inside of the tank is a post 212 similar to the post 12. One of the bracing plates inside of the tank similar to the plate 17 is indicated by 217 and this has its straight edge reinforced by angle-irons 217a.

The modification shown in Fig. 7 resembles 40 that shown in Fig. 6 except that the side wall is composed of two frusta of cones instead of four. Corresponding parts are indicated by corresponding reference numerals augmented by 100.

45 In Fig. 8 I have suggested a form employing one or more cylindrical sections with one or more frusta of cones. As here shown, there are three courses, the middle 414 being cylindrical, the upper 413 being a frustum of a cone and the lower 416 being also a frustum of a cone. The top is indicated by 410 and the bottom by 411. As here shown, I employ internal stiffener plates 417.

In Fig. 9 I have shown a tank similar to that 50 shown in Fig. 3 except that instead of using

external stiffening plates, I employ horizontal stiffeners 517 on the outside of the tank. As here shown, these stiffening rings are located at the intersections of the frusta; although it is obvious that they may be placed at other points on each course. These stiffeners may be either plates or shapes.

It is to be understood that in all cases bracing plates may or may not be used and may be placed either inside or outside of the tank or both.

In Figs. 10-12 I have shown profile diagrammatic sketches indicating several alternative constructions all of which utilize the polyconic principle to gain stiffness in the shell. In Fig. 11 the courses are joined by horizontal stiffeners 617.

In Fig. 13 I have shown a shell with no conical surfaces at all but employing merely a series of cylindrical courses of different diameters offset from each other by the horizontal stiffening members 717.

While I have shown and described certain embodiments of my invention, it is to be understood that it is capable of many modifications. Changes, therefore, in the construction and arrangement may be made without departing from the spirit and scope of the invention as disclosed in the appended claim, in which it is my intention to claim all novelty inherent in my invention as broadly as permissible, in view of the prior art.

What I claim as new, and desire to secure by Letters Patent, is:

A sheet metal pressure tank, comprising: a side wall formed of frusta of cones axially arranged and circumferentially connected together in superimposed relation, said upper frusta of cones tapering downwardly and inwardly and said lower frusta of cones tapering upwardly and inwardly; and a substantially flat top and bottom.

ARNOLD H. HEINEMAN.
